UNITED STATES PATENT OFFICE

2,212,793

ANTIDAZZLE DEVICE

Walter James Rex, Hatch End, England

Application June 5, 1939, Serial No. 277,545
In Great Britain September 13, 1937

2 Claims. (Cl. 40—132)

This invention seeks to provide an improved antidazzle device for a lamp, and may be said to consist in an antidazzle device comprising one or more sections of closely-disposed thin glass or other transparent parallel strips placed edge-wise with respect to the light source, said strips having at least one surface ground or similarly treated so that direct projection of light takes place only through the edges of the strips with no appreciable reflection off or projection through the ground surface or surfaces.

The invention further contemplates placing behind an antidazzle device such as that immediately-above described certain other transparencies; for instance it has been found that where the laminations of the previously-proposed glass extend horizontally, the provision behind that glass of a further sheet of glass with vertical ribs or laminations tends to spread the light laterally without any tendency to increase the spreading upwards or downwards. Again, certain coloured glasses have the effect of dimming the light considerably so as to render it practically invisible from any point out of the useful plane of illumination.

In the accompanying diagrammatic drawing forming part of this specification and in which like numerals are employed to designate like parts throughout the same:

30 Figure 1 is a perspective view of one of the glass strips used in the antidazzle device;

Figure 2 is a sectional side elevation illustrating an illuminated sign employing an antidazzle device and in addition certain other transparencies for purposes which will become apparent from the following description; while

35 Figure 3 is a sectional side elevation similar to Figure 4 but illustrating a modified and more simple form of sign.

40 Figure 4 is a detail plan view better showing the clip mounting for supporting ends of the reflector.

Referring now to the drawing the casing 12 is divided into a hollow top part providing a lamp chamber 13 and a hollow bottom part 14 for accommodating a battery. The lamp chamber 13 has an opening which is closed by a block made up of transparent laminations 9, as shown in Figure 1, preferably having both faces ground as indicated at 11 in Figure 1. In addition the ground surfaces are preferably coated with dull black paint or adhesive before being placed together. The object of the present form of the invention being to spread the light laterally without projecting it upwards, the laminations 9 are

of course arranged horizontally. The block of laminations 9 is received within the carrying frame composed of the guides 15 and 16 which are attached to the casing at the forward ends and have their inner ends turned over, as indicated at 17, to serve for retaining the block and such other members as may be used therewith, as will be referred to later.

In addition to the block of laminations 9, there are illustrated in Figure 2 further transparencies 18, 19 and 20 which are received within the guides 15 and 16 behind the block of laminations. The front transparency may include written matter appropriately placed thereon and may in some cases be ribbed vertically or horizontally to assist in directing the light according to requirements. The transparencies 19 and 20 may be variously coloured; for example the transparency 19 may be red and the transparency 20 green, which two colours in combination have been found to produce a light which is practically invisible from any point outside the very limited angle through which the matter displayed by the sign can be seen.

For illumination of the matter of the transparency 18, there is provided a bulb 21 which derives its source of current from a battery 14a in the box 14. The bulb conveniently is mounted on the horizontal wall 22 which separates the light chamber 13 from the battery box 14. The adapter 23 in which the bulb 21 is carried is preferably supported upon rods 24 so that it can be raised or lowered to get various desired results.

There may be provided a reflector as indicated at 25 the purpose of which is to reflect light through the display panel of the sign, and the reflector may be adjustable; although generally speaking it will not need to be adjusted once it has been erected in the desired position. For effecting the initial adjustment, the reflector 25 is located by metal clips 26 and 27 adapted to be turned up to engage the reflector in position across the top corner of the casing when it has been properly located. For adjustment one or both of the clips 26 may extend from a plate which is adjustable along a guide 28, as shown for instance with reference to the clip 27.

The arrangement shown in Figure 2 has been devised as a sign which would be particularly useful for providing an effective illuminated sign visible under all conditions of the required normal use but practically invisible outside the required normal field of view. Thus, such an il-

luminated sign may be particularly useful, for instance, during air raids.

As shown in Figure 2, the arrangement has only a front display panel and on the back of the casing there will generally be provided bands 30 by means of which the casing can be attached to a standard or post. If there are four display panels, one on each side wall of a rectangular casing, the casing will then either be supported on the top of the post or directly upon the ground and arrangements for securing it will then be made accordingly.

Although in the Figure 2 arrangement it has been preferred to illustrate the sign as a self-contained apparatus including a battery, the battery box may be dispensed with and the bulb 21 then illuminated from some available source of current.

The arrangement illustrated in Figure 3 merely serves to show a very much more simple form of illuminated sign working on the same principle as that illustrated in Figure 2. The casing 31 is shaped to fit the block of laminations 9 arranged in the same way as those of the display panel in the Figure 2 arrangement, and the back of the casing is curved, as shown at 32, for the reception of a curved reflector 33 secured to the casing in any convenient manner. The block of laminations is backed by the transparencies 18, 19 and 20 as described with reference to Figure 2. If the display panel should happen to be round when viewed from the front, the ribs of the transparency 18 may be concentric.

It will be obvious that in all examples of the invention many modifications may be made without departing from the scope of the claims; for instance the glass strips may be cemented with coloured paint or cement in certain cases. Thus, if red cement is used and a green glass is placed behind the laminations the reflection is very considerably deadened. Again, in another case yellow glass may be used behind the laminations and blue glass in front.

What I claim is:

1. An illuminated sign including a casing, a wall dividing the casing into a hollow top part and a hollow bottom part, said hollow top part having

an opening, a reflector carried in the hollow top part on the top and rear walls and opposite the opening, means for adjusting the reflector to different angles with respect to the opening, guide members surrounding the opening in the hollow top part, transparent strips mounted in superposed face to face engagement between the guide members and having corresponding edges presented to the opening, a display element behind the strips, an adapter, a light bulb mounted on the adapter, a source of current in the bottom part, and connections between the source of current, the adapter and the light bulb, said bulb being energizable by the source of current for projecting beams to be reflected by the reflector to project through the transparent strips for providing illumination and said adapter being operable for shifting the bulb with respect to the reflector and opening.

2. An illuminated sign including a casing, a wall dividing the casing into a hollow top part and a hollow bottom part, said hollow top part having an opening, supporting means for the casing, said hollow top part having a top wall and a rear wall, guides on the inner surfaces of the top wall and rear wall, adjustable clips slidably mounted in the guides, one of said clips being mounted on the top wall and the other of said clips being mounted on the rear wall, a reflector carried in the hollow top part and extending between the clips, said clips being shiftable for adjustably mounting the reflector in the hollow top part, guide members surrounding the opening in the hollow top part, transparent strips mounted in superposed face to face engagement between the guide members and having corresponding edges presented to the opening, a display element behind the strips, a source of current in the hollow lower part, an adapter mounted on the wall, a light bulb carried by the adapter, and connections between the current source and the bulb, said bulb being energizable by the source of current for projecting beams to be reflected by the reflector to project through the display element and transparent strips.

WALTER JAMES REX.
